PC(57) **CLAIM**

The ornamental design for an extrusion for a glazing assembly, as shown and described.

DESCRIPTIONFIG. 1 is a perspective view of the extrusion for a glazing assembly showing my new design; and,
FIG. 2 is an elevational end view of the extrusion for a glazing assembly.

The extrusion for a glazing assembly is shown with a symbolic break in its length. The appearance of any portion of the extrusion for a glazing assembly between the jagged break lines forms no part of the claimed design.
